UNITED STATES PATENT OFFICE.

FRANZ BURGER, OF FORT WAYNE, INDIANA, ASSIGNOR OF THREE-FOURTHS TO HENRY M. WILLIAMS, OF SAME PLACE.

INTERMITTENT ELECTRIC SURFACE CONDUCTOR.

SPECIFICATION forming part of Letters Patent No. 614,082, dated November 15, 1898.

Application filed July 23, 1897. Serial No. 645,715. (No model.)

To all whom it may concern:

Be it known that I, FRANZ BURGER, a citizen of the United States, residing at Fort Wayne, Allen county, State of Indiana, have 5 invented certain new and useful Improvements in Intermittent Electric Surface Conductors, of which the following is a specification.

My invention relates to electric railways, 10 and more particularly to that class of electric railways in which there is an intermittent electric surface conductor arranged in proper relation to the tracks, so that as the trolley or train or car passes over the track the current will be supplied thereto through the intervention of the intermittent electric contacts with the main feeding-conductor.

The object of my invention is to improve 15 and simplify the construction of such electric railways and to overcome the difficulties inherent to the overhead trolley-wire and the usual form of underground-conduit construction, as well as to provide a construction which is applicable to railway-lines already 20 in use, without the necessity of building expensive conduits. In order to accomplish this and other objects which will be apparent to those skilled in the art, my invention consists in the features of construction substantially as hereinafter more particularly set 25 forth.

Referring to the accompanying drawings, 30 wherein I have illustrated a preferred embodiment of my invention, although it is to be understood that my invention is not limited 35 to the precise details of construction shown, Figure 1 is a transverse section of a railroad embodying my invention, and Fig. 2 is a longitudinal section of the same. Fig. 3 is an 40 enlarged detail.

In order to show the simplicity and practicability of my invention, it is illustrated in connection with an ordinary tram or other railway, in which A are the cross-ties of the 45 road, on which the rails B B are secured in the usual manner. Arranged between the rails B B, and in this instance bearing directly upon the cross-ties A, is a stringer C, which may be secured in any desired manner 50 and which is preferably covered with asphaltum or some other insulating and preserving

material. Mounted upon this stringer C is the feeding-conductor D, which may be in sections of any desired length and secured to the stringer in any well-known manner, and 55 connected to the feeding-conductor are the branch wires e, secured to the main leading-conductor E, which is insulated in any suitable way and arranged preferably adjacent to the stringer, being connected to the feeding-wires at proper and desirable intervals by the branches e.

Mounted upon the stringer is a channel-shaped covering F, made of some flexible, waterproof, and elastic material, preferably 60 of rubber, and this is secured at its edges to the stringer by any suitable means and forms an intervening space G between the feeding-conductor D and the covering F, and this space may be filled with an elastic fluid—as, 65 for instance, compressed air—which tends to maintain the covering F out of contact with the conductor. This flexible elastic covering F is provided with a series of metallic contact-pieces H, which extend through perforations in the covering near its longitudinal center, and they are arranged at suitable distances apart, so that when the trolley-wheel T passes over them it will make contact with one before it leaves the other. 70 These contacts may be of different shape and construction, but as shown they are provided with flattened heads on each side of the covering, being connected thereto through perforations in the covering which are air and 75 water tight.

In order to protect the flexible covering and keep it in place, I provide channel-irons I, which, as shown, are of any ordinary commercial form and are arranged on each side 80 of the covering, being secured to the stringer in the present instance by bolts I'. These channel-irons are arranged so that they do not meet at the top, but so that there is a narrow slot between them too small to permit the 85 entrance of an ordinary vehicle-wheel, but large enough to permit the entrance of the trolley-wheel T. In the present instance the channel-irons bear upon the edges of the flexible covering, which forms of itself a gasket or 90 packing between the channel-irons and the stringer, producing an air and water tight con- 95

nection. The adjacent edges of the channel-
irons I are preferably insulated, as shown at
i, in any suitable way to prevent any possible
leakage between the contacts and the trolley-
wheel, or the trolley-wheel itself may have in-
sulated sides or be otherwise arranged to pre-
vent electric contact with the channel-irons.

With this construction it will be seen that
under normal conditions the contacts II are
10 supported above the feeding-conductor by the
resiliency or elasticity of the flexible cover-
ing, aided or not by an elastic medium within
the covering, and the feeding-conductor is
15 maintained entirely free from water or other
substance which could in any way cause leak-
age or danger from the electric current, and
there is no possibility of short-circuiting the
same. When, however, the trolley-wheel T or
20 similar device passes through the slot be-
tween the adjacent edges of the channels and
bears on the contact-pieces II, they are pressed
down in contact with the feeding-conductor
as the trolley passes along, conveying current
25 from such feeding-conductor through the con-
tact-pieces to the trolley and the motor on the
car, and as soon as the trolley-wheel passes

from a contact-piece it is restored to its nor-
mal position by the resiliency of the covering.

What I claim is—

An intermittent electric surface conductor, 30
comprising a stringer mounted on the cross-
ties, a feeding-conductor supported on the
stringer, a flexible covering for the conduc-
tor secured to the stringer and having a se-
ries of contact-pieces extending through the 35
covering, channel-irons arranged on each side
of the flexible covering and secured to the
stringer leaving a slot between their adjacent
edges, and insulating material applied to the
40 adjacent edges whereby when the trolley-
wheel passes through the slot the contact-
pieces are pressed into engagement with the
feeding-conductor and rise therefrom by the
resiliency of the covering, substantially as de-
scribed.

In testimony whereof I have signed my
name to this specification in the presence of
two subscribing witnesses.

FRANZ BURGER.
